FUEL PUMP

William F. Bahr, Glen Ullin, N. Dak.

Application January 13, 1937, Serial No. 120,447
Renewed August 16, 1938

1 Claim. (Cl. 221—77)

This invention relates to liquid dispensing devices and more particularly to a liquid dispensing means of the pressure type adapted for dispensing fuel, oil, or the like.

An object of this invention is to provide a pressure operated means which may be engaged with a conventional liquid holding receptacle so that the liquid in the receptacle may be dispensed, as may be desired, by means of a liquid dispensing valve or nozzle.

Another object of this invention is to provide a pump of this character which may be threadably engaged with a barrel or like receptacle in which fuel or oil is received so that a person may readily dispense the fuel or oil from the barrel, the fuel being under air pressure so that the fuel or liquid will be forced into the dispensing hose and out through the dispensing valve or nozzle.

A further object of this invention is to provide a readily detachable dispensing means in the form of an air pump and a liquid dispensing line which may be detachably engaged with different sizes of containers or barrels so that a person residing on the farm or the like may buy fuel or oil in different sized containers and conveniently dispense the fuel or oil directly to a tractor or the like, thus eliminating the necessity of taking the liquid out of the container into a smaller container and then pouring the liquid into the vehicle or tank, as may be the case.

With the foregoing and other objects in view, the invention will be more fully described herein-after, and will be more particularly pointed out in the claim appended hereto.

In the drawing, wherein like symbols refer to like or corresponding parts throughout the several views,

Figure 1 is a detail side elevation partly broken away and in section of a barrel having a liquid dispensing means constructed according to an embodiment of this invention mounted thereon.

Figure 2 is a fragmentary vertical section of the dispensing means.

Referring to the drawing, the numeral 10 designates generally a barrel of suitable capacity, such as is commonly used for holding liquid fuel or oil and which is provided in one end thereof with a threaded boss 13 and a threaded plug 11. The boss 13 is adapted to be used for removing the liquid from the barrel 10 and the plug 11 is preferably inserted in the intake opening of the barrel 10.

In order to provide a means whereby the fuel or liquid 12 positioned within the barrel 10 may be conveniently and quickly removed from the

barrel 10 with the barrel standing on end, I have provided a dispensing means comprising a pipe 14 which is adapted to extend downwardly through the boss 13 and into the interior of the barrel 10. This pipe 14 at its inner end is provided with a nipple 15 having a strainer 16 secured therein and preferably the lower end of the nipple 15 is notched, as at 17, so that the nipple 15 may contact directly with the inner surface of the bottom 18 of the barrel 10.

A flexible hose 19 has one end thereof secured, as by a clamping device 20, to the upper or outer end of the discharge pipe 14 and a relatively stiff wire 21 is wound about the hose or flexible member 19 adjacent the point of connection between this hose 19 and the upper end of the pipe 14 so as to prevent kinking of the hose 19. A discharge valve 22 of conventional construction is secured to the opposite or outer end of the hose 19 and is provided with a lever or operating member 23.

An air pressure casing 24 is disposed loosely about the pipe 14 and at its lower end is provided with stepped threaded portions 25 of different diameters so that the lower end of the casing 24 may be threaded into the outlet openings of barrels which are of different diameters. In this manner, it is not necessary to provide a special coupling means for barrels of different sizes and which may be provided with a particular outlet opening in each size.

The lower end of the casing or housing 24 is provided with an annular flange 26 which is adapted to engage the outer edge of the boss 13 and a gasket or like sealing member may be interposed between the flange 26 and the boss 13 so as to properly seal the housing 24 on to the barrel 10. The opposite or outer end of the housing 24 is provided with a seat 27 against which a sealing member or gasket 28 is adapted to engage. A nut 29, having opposed ears 30, is threaded into the upper end of the casing 24 and is adapted to press the gasket 28 against the tapered seat 27 so that this gasket 28 will hold the pipe 14 against movement relative to the casing 24 and also seal the pipe 14 in the casing 24. As shown in Figure 2, the lower end of the casing 24 is provided with a relatively large bore 31 which is disposed loosely about the pipe 14 so that air from the casing 24 may flow downwardly into the interior of the barrel 10.

A pump cylinder 32 is threaded, as at 33, into a side of the air chamber or housing 24 and is provided with a plunger 34 having a rod 35 secured thereto which extends outwardly through the outer end 36 and is provided with an operat-

ing handle 37. The end 36 is provided with an inlet opening 38 so that air may readily enter the cylinder 32 on the outer side of the plunger 34. The inner end 39 of the pump cylinder 32 is provided with an axial opening 40 which is closed by an inwardly opening check valve 41. The valve 41 is provided with a pair of opposed arms 42 which loosely engage guide members 43 carried by the inner end 39. An air relief valve 44 is threaded into the casing 24 and is adapted to be opened when it is desired to relieve the air pressure within the interior of the barrel 10.

The discharge nozzle 22 may be held in inoperative position by means of a supporting device 15 comprising a U-shaped clip 45 secured to a standard 46 which is provided with a clamp 47 which is clamped about the pipe 14. It will be understood that either the nozzle 22 or the hose 19 may be engaged in this supporting clip 45 so as to hold the nozzle 22 in a manner to prevent the nozzle from coming into contact with dirt or the like.

In the use and operation of this dispensing means, the pipe 14 is inserted into the barrel 10 until the inner end 15 thereof contacts with the bottom 18. At this time, the nut 29 is relatively loose in the upper end of the housing 24 so that the housing 24 may then be moved downwardly with respect to the pipe 14 for threaded engagement with the threaded boss 13. By means of the nut 29, the device hereinbefore described may be used with barrels of different heights, this being possible by the slideable mounting of the pipe 14 in the housing 24 so that the pipe 14 may be readily adjusted to fit into any size of barrel with the inner end 15 engaging the bottom of the barrel and then the nut 29 tightened so as to seal the pipe 14 relative to the housing 24. The housing 24 may then be tightly threaded 40 into the boss 13 whereupon the nut 29 may be

turned to seal the pipe 14 with respect to the housing 24. The pump operating member 31 may then be operated so as to place the desired air pressure within the interior of the barrel 10. The valve member 22 may then be engaged with the desired receptacle and the lever 23 operated so as to discharge the desired quantity of liquid from the barrel 10.

It is, of course, understood that various changes and modifications may be made in the 10 details of construction and design of the above specifically described embodiment of this invention without departing from the spirit thereof, such changes and modifications being restricted only by the scope of the following claim.

I claim:

A liquid dispensing means for use with a receptacle containing liquid, comprising a housing, a threaded nipple carried by one end of said housing and constituting means to secure the 20 housing onto said receptacle, a liquid discharge pipe extending vertically through said housing and said nipple, the exterior surface of said pipe being disposed in spaced relation to the interior surface of said nipple, a gland threadably engaging the opposite end of the housing and engaging about said pipe in a manner to seal said pipe in the upper portion of said housing and to support said pipe from said housing, an air pump secured to said housing intermediate the ends thereof, said air pump including a cylinder, an inner wall carried by said cylinder having an opening therethrough, a check valve for said opening carried by said end wall, said check valve opening inwardly of said housing, a plunger 30 slideable in said cylinder, operating means for said plunger, and a relief valve secured to said housing.
